(57) **CLAIM**

The ornamental design for an isolation clean booth, as shown and described.

DESCRIPTION

FIG. 1 is a front, top, and right side perspective view of an isolation clean booth according to the design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a cross-sectional view taken along line 8-8 of FIG. 2;

FIG. 9 is a cross-sectional view taken along line 9-9 of FIG. 4; and,

FIG. 10 is an enlarged view of the portion shown in BOX 10 in FIG. 9.

The broken lines illustrate portions of the isolation clean booth that form no part of the claimed design. The hatching shown in FIG. 8, FIG. 9, and FIG. 10 represents unclaimed subject matter and forms no part of the claimed design. The long and short dash broken lines in FIG. 9 and FIG. 10 are
